his Attorney.

UNITED STATES PATENT OFFICE.

JOHN B. LOTT, OF ANDERSON, INDIANA.

MEANS FOR CONNECTING RAILROAD-RAILS TO CEMENT FOUNDATIONS.

1,193,573.

Specification of Letters Patent.

Patented Aug. 8, 1916.

Application filed November 16, 1915. Serial No. 61,837.

To all whom it may concern:

Be it known that I, JOHN B. LOTT, a citizen of the United States, resident of Anderson, in the county of Madison and State 5 of Indiana, have made a certain new and useful Invention in Means for Connecting Railroad-Rails to Cement Foundations; and I declare the following to be a full, clear, and exact description of the same, such as 10 will enable others skilled in the art to which it appertains to make and use the invention, reference being had to the accompanying drawings, and to letters or figures of reference marked thereon, which form a part of 15 this specification.

Figure 1 is a sectional view of the invention as applied. Fig. 2 is a detail side view of the parts of the invention. Fig. 3 is a 20 sectional view of a modification of the invention as applied. Fig. 4 is a detail side view of a modified form of anchor bolt. Fig. 5 is a plan view of the invention as applied.

The invention has relation to improved 25 means for bolting or connecting railroad rails to a cement foundation or base, having for its object to strengthen or solidify the connection and to render the making of repairs more easy.

The invention consists in the novel 30 construction and combination of parts, as hereinafter set forth.

In the accompanying drawings, illustrating 35 the invention, the numeral 2 designates the cement foundation or bed, which may be provided with suitable conduits 3 for gas pipe, electric wires and the like, this foundation being preferably molded "in situ," one course for each rail.

4 designates anchor plates, around which 40 the cement material of the foundation is molded, said plates having upstanding bosses 5, 5, provided with internally threaded seats for the lower threaded ends of anchor bolts 6, 6, around which the cement 45 material is also molded, said bolts extending upwardly nearly to the top surface of the foundation and being provided with enlarged, internally-threaded upper ends 7, 7, providing seats 8, 8 for the lower threaded 50 ends of the bolts 9, 9 connecting the steel rails to the foundations. Should these

bolts 9, 9 become broken or the thread stripped therefrom, they may be readily removed and replaced by new ones.

The cement foundation or courses for the 55 two rails may be suitably connected by cross-ties 10, 10, of wood or the like. A cushion board 11 may be placed between the cement foundation and the rail. It is preferred that the foundation be of T form, 60 having lateral extensions 12, 12 to brace the foundation against movement and to afford additional space wherein conduits may be located.

A modification is shown in Fig. 3, wherein 65 the anchor plates designated 4' are located at the bottom of the cement foundations, and the anchor bolts designated 6' have lower nuts 14, engaging said plates.

A further modification is shown in Fig. 4, 70 wherein the anchor bolts, designated 6'', have each a lower head designated 4'', constituting the anchoring means.

I claim:

1. Means for connecting railroad rails to 75 cement foundations, consisting of a cement foundation, an anchoring means, anchor bolts inclosed by the cement material of said foundation and having lower ends connected with said anchoring means, and enlarged, internally-threaded upper ends to 80 provide seats, and surface bolts extending through the rail flanges and engaging said seats.

2. Means for connecting railroad rails to 85 cement foundations, consisting of a cement foundation, an anchor plate inclosed by the cement material of the foundation and having upstanding internally-threaded bosses 90 to provide seats, anchor bolts also inclosed by said cement material and having lower threaded ends engaging said seats, and enlarged upper internally-threaded ends to provide seats, and surface bolts extending through the rail flanges and engaging said 95 seats of the anchor bolts.

3. Means for connecting railroad rails to cement foundations, consisting of T-form cement foundations underlying and parallel to the rails, an anchor plate inclosed by the 100 cement material of each foundation and having upstanding, internally-threaded

bosses to provide seats, anchor bolts also inclosed by said cement material and having lower threaded ends engaging said seats, and enlarged upper internally-threaded ends 5 to provide seats, and surface bolts extending through the rail flanges and engaging said seats of the anchor bolts.

In testimony whereof I affix my signature, in presence of two witnesses.

JOHN B. LOTT.
